UNITED STATES PATENT OFFICE.

WILSON A. WILHELM, OF VERNON, TEXAS.

OIL GRATE AND MAT.

Application filed September 11, 1925. Serial No. 55,885.

This invention relates to a combined oil grate and mat especially adapted for use in hydraulic oil presses.

Briefly stated, one of the objects of this invention is to provide simple and novel means whereby an oil grate and mat may be combined in one structure in such a manner that the oil channels for the collection and passage of oil may be increased in size as compared with the oil channels of the grates of other hydraulic oil presses of which I am aware, and a further aim is to provide simple means whereby the openings for supplying the oil to said oil channels may be increased in cross sectional area and substantially shortened, all of which increases the efficiency of the invention.

A further and equally important object of the invention is to provide a combined oil grate and mat in which the oil channels may be easily cleaned at any time without removing the mat or any of the other parts of the press.

A further object of the invention is to provide a combined oil mat and grate which will displace the separate mat and grate employed in hydraulic oil presses and which may be applied to standard oil presses without substantial alteration of the same.

Another object is to provide a combined oil grate and mat which by reason of the consolidation of the grate and mat will overcome the need of employing rivets and screws which ordinarily pass through the mat and through the grate and often loosen and back out, thereby causing destruction of the press cloths and interfering with the rapid placing of cake into box or removing the same from box by the cake pan striking said rivets or screws.

A further and equally important object is to provide a combined oil grate and mat which consists principally of a plurality of interlocked parallel bars which by reason of their peculiar interlocking connection will possess sufficient yieldability with no loss of strength and will avoid possible shearing action.

In the accompanying drawing forming a part of this application and in which like numerals are employed to designate like parts throughout the same,

Figure 1 is a perspective of the combined oil grate and mat in place.

Figure 2 is a fragmentary plan view of the same.

Figure 3 is a fragmentary side elevation of the improved oil grate and mat and the holding strap for the same.

Figure 4 is a detail elevation illustrating one end portion of the combined grate and mat.

Figure 5 is a fragmentary perspective illustrating one of the bars of the improved grate and mat.

Figure 6 is a fragmentary side elevation of the improved combined oil grate and mat.

Figure 7 is a fragmentary plan view of one of the bars of the improved combined grate and mat.

Figure 8 is a fragmentary plan view of a slight modification of the invention.

Figure 9 is a fragmentary side elevation of the form of combined mat and grate illustrated in Figure 8.

Figure 10 is a fragmentary perspective of the form of bar shown in Figures 8 and 9.

Figure 11 is a fragmentary plan view of the form of bar illustrated in Figures 8, 9 and 10.

Figure 12 is a fragmentary side elevation of the form of bar shown in Figures 8, 9, 10 and 11.

In the drawing wherein for the purpose of illustration is shown a preferred embodiment of the invention, the numeral 5 designates one of the body plates of an oil press, which body plate is attached to the press in the usual and well known manner. As is known the body plate ordinarily supports a grate and a mat is mounted upon the grate. However, in accordance with this invention the grate is combined with the mat and the unitary structure thus produced is bolted by cap screws or other fastening devices 6 to the body plate.

Referring first to the form of the invention illustrated in Figures 1, 2, 3, 4, 5 and 6 it will be seen that the combined grate and mat consist of a plurality of more or less similarly formed movably connected bars 7. Figures 5 and 6 illustrate that one side of each bar 7 is provided with a longitudinal rib 8 adapted to be received in a longitudinal groove 9 of an adjacent bar, whereby all of the bars are interlocked, this construction providing a sufficiently yieldable arrangement to avoid destruction of the combined grate and mat to avoid breaking as a result of excessive pressure. Figure 6 illustrates that the bars are provided with a plurality of aligned openings 10 for the

reception of suitably stout rivets or other fastening devices 13, by means of which all of the bars are securely joined to provide a unitary and sufficiently rigid structure without interfering with the yielding or rocking movement of the bars relatively to each other. Attention is now directed to the fact that the side walls of the bars are provided at a point near the upper surfaces thereof with longitudinal channels or grooves 11 which receive oil from vertical grooves 12. The oil channels 11 open out through the ends of the combined grate and mat and provide a simple and reliable means for collecting the oil which is supplied to the openings 12 and for conducting this oil through one end of the grate. The channels 11 are arranged in opposed relation as are the substantially vertical grooves 12. When the channels become clogged, it is a simple matter to clean the same with a metal swab or with a steam or air line. This may be accomplished without dismantling the machine or without detaching any of the parts thereof.

Attention is directed to the fact that the bars are provided with transverse channels 16 having restricted branches or mouths 17 which open out through the top of the bars and receive a portion of the oil pressed from the material. Of course the transverse grooves or channels 16 which open out through the opposite sides of the combined grate and mat provide a transverse drainage while the longitudinal grooves or channels 11 provide longitudinal drainage. It is thus seen that the improved combined grate and mat is provided with simple means whereby longitudinal as well as transverse drainage for the oil is provided. As the slot 17 extends entirely across the surface of the structure an adequate inlet is provided for the oil and the maximum quantity of oil is therefore recovered.

In carrying out the invention the ends 45 of the bar are formed with transverse grooves 20 for the reception of the angle plate 21, the angle plate or strap 21 being securely held in place by cap screws or other fastening devices. The cap screws may enter holes vacated by the former clip screws or new holes drilled for the purpose. The shape of the holding down strap 21 is such that the oil channels are in no way obstructed. Hence free drainage of oil and 50 ease of cleaning the channel is provided.

Attention is directed to Figure 4 which shows that the grooves 12 (of Fig. 2) which extend through the head of the bar to the channels 11 are tapered and therefore some- 55 what increased in diameter in cross sectional area toward the lower end thereof to provide for the free passage of the oil from the oil bearing substance to the longitudinal and transverse channels.

65 In the form of invention illustrated in

Figures 8 to 12 inclusive the combined grate and mat is designated by the numeral 30 and comprises a number of bars 31. One side of each bar is provided with a longitudinal tongue extending for the full length thereof and adapted to be received in a groove 33 of an adjacent bar, whereby all of the bars when properly assembled form a substantially unitary structure. The bars are provided with openings 34 for the reception of rivets 35 or other suitable fastening devices.

70 The transverse grooves 36 in the ends of the combined grate and mat are adapted to receive the inner edge portion of holding straps 37, which holding straps are securely held in place by screws 38 or similar fastening devices.

75 Figure 10 well illustrates that each bar 31 is provided in the opposite side faces thereof with grooves or channels 40 which communicate with adjacent channels since all the channels are in opposed relation as clearly shown in the drawing. Figure 10 and Figure 12 illustrate that the oil which is pressed from the oil bearing substance flows from the 80 face of the structure through vertical grooves 41 and into the channels 40. When the oil enters the channels 40 it is conducted to one end of the combined grate and mat and is collected as is obvious.

85 With reference to the foregoing description taken in connection with the accompanying drawings, it will be seen that a combined grate and mat constructed in accordance with either form of the invention is 90 provided with ample drainage to conduct the oil from the oil bearing surface to a point of collection in a highly expeditious manner and without the possibility of breakage as a result of the great pressure employed.

95 Particular attention is directed to the fact that the openings or grooves 11 and 41 are substantially shorter and are greater in cross sectional area than the grooves heretofore employed in mats and they therefore provide 100 for the more rapid drainage of the oil and are not so easily clogged.

105 Attention is also invited to the fact that no rivets or screws pass through the mat into the grate. In this connection it might be 110 stated that such rivets or screws in the conventional mat tend to loosen and back out causing destruction to press cloths and interfering with rapid placing of material into box or removing same from box by the cake 115 pans cleaning and cake removing tools striking the loose rivets or screws. This invention does not employ a mat plate and consequently no screws or rivets extend through such plate to the grate.

120 Since the structure is made up of a number of parallel bars having the tongue and groove connection illustrated all of the bars are properly matched and the desired construction and stability is obtained with no 125

loss of strength and no possible shearing action of the bars is permitted.

With reference to the foregoing description taken in connection with the accompanying drawings, it will be seen that the invention combines all of the advantages of a separate grate and mat and has appreciable advantages resulting from such combination.

- 10 Slots 12 of Figure 2 may be cut the full length of bar, i. e. one continuous slot, so that when placed beside other similar bars form complete longitudinal drainage into channels.
- 15 The face of mat would then have a complete cross checked drainage as shown in Figure 1.

The conventional corrugations may be cut on face of mat to suit users. These corrugations may be on center lines of slots, longitudinal and transverse, or midway between them.

I claim:

1. An oil grate and mat combined in a unitary structure and comprising a plurality of interlocked movably connected parallel bars arranged with their sides contacting, means extending transversely through said bars to hold them assembled, each bar being provided in each side wall near its upper surface with a longitudinal groove, the grooves of adjacent bars registering when assembled to form oil receiving or collecting channels opening through the ends of the structure whereby the collected oil may be

conducted to a suitable place of deposit, a plurality of longitudinally spaced vertical passages leading from said channels through the upper face of the bars to provide oil feeds for the channels, said bars also having 40 transverse channels arranged in a plane above the longitudinal channels and provided with restricted slot-like mouths opening through the tops of the bars to provide 45 a transverse drainage for the structure.

2. An oil grate and mat combined in a unitary structure and comprising a plurality of interlocked movably connected parallel bars arranged with their sides contacting, each bar having near its bottom portion a 50 longitudinally extending rib on one side face and a longitudinal groove on its other side face, the groove of one bar being designed to receive the rib of an adjacent bar whereby all of the bars are interlocked and movably 55 connected to avoid breakage resulting from excessive pressure, means extending transversely through said bars to hold them assembled and provide a unitary structure, channels extending longitudinally and trans- 60 versely of said structure, the longitudinal channel being arranged in a plane below the transverse channel and each set of channels having mouths leading through the tops of the bars to form feed openings for the respective channels whereby transverse and longitudinal drainage for the structure is 65 provided.

WILSON A. WILHELM.
